UNITED STATES PATENT OFFICE.

LOUIS PRIEST, OF FLINT, MICHIGAN, ASSIGNOR TO TRUMAN W. WHITNEY, OF ST. LOUIS, MISSOURI, AND CHARLES N. MORSE, OF FLINT, MICHIGAN.

VEHICLE-BOX.

SPECIFICATION forming part of Letters Patent No. 691,661, dated January 21, 1902.

Application filed October 18, 1900. Renewed December 5, 1901. Serial No. 84,787. (No model.)

To all whom it may concern:

Be it known that I, LOUIS PRIEST, a citizen of the United States, residing at Flint, county of Genesee, State of Michigan, have invented 5 a certain new and useful Improvement in Vehicle-Boxes; and I declare the following to be a full, clear, and exact description of the invention, such as will enable others skilled in the art to which it pertains to make and 10 use the same, reference being had to the accompanying drawings, which form a part of this specification.

This invention relates to vehicle-boxes, and has for its object an improved construction of box to be employed with a light wagon or buggy in which the timbers employed in constructing the box are secured together without the use of nails or bolts, but by means of dovetailed locking-blocks or binding-blocks so arranged that the several parts when put together in order are held and are finally bound together by the insertion of one or more key-blocks that retain all the parts in position so long as the key-blocks themselves remain in position. In connection with the essential parts I also use corner binding-pieces which may be inserted either before or after the final binding key-blocks are inserted and which are used because the 25 timbers ordinarily employed in structures of this kind do not retain the exact shape and form to which they are originally cut unless they are held from warping and twisting away from such form. The corner-blocks referred to are practically useful, but would not be necessary except for the unstable character of the material.

The buggy or wagon box is made of a bottom frame of four pieces, inclosing boards of four 40 pieces, two side boards, and two end boards, a seat-support, preferably constructed of eight pieces, and the corner-binders hereinbefore referred to, which are generally twelve in number.

45 In connection with the box there is a seat constructed on the same principle and which is not made to be connected by binding-blocks or key-blocks to the seat-support, but is adapted to be secured thereto by bolts. 50 The seat itself is constructed, like the box, of a bottom frame, a back, and two ends or

arm-rests at the ends, bound together by tie-blocks in substantially the same way as the vehicle-box.

In the drawings, Figure 1 is a plan view of 55 the vehicle-box and seat-support. Fig. 2 is a perspective of a side and end of the seat-support. Fig. 3 is a perspective of the bottom and one side of the box and of the seat-support properly located with respect to the side 60 and bottom. Fig. 4 is a detail of a corner of the bottom frame. Fig. 5 is a perspective of the key-block. Fig. 6 is an elevation of one side of the vehicle-box. Fig. 7 is a perspective of the seat. Fig. 8 is a plan view of the 65 seat and the seat-bottom. Fig. 9 is a perspective of an end or arm rest of the seat.

In Figs. 1, 2, 3, and 6 the parts are shown as though they were broken, this system being adopted because in an actual vehicle-box 70 the side boards and timbers would be from four to eight feet long, while the thickness of the timbers employed would some of them be half an inch and others an inch and a half, and the attempt to preserve the proper proportions would make some parts of the drawing so small that it would be difficult to understand it, and it is necessary either to show the parts as broken in the way suggested or to consider them as entirely out of their true 75 proportion.

The bottom of the box consists of four pieces 2, 2^a, 2^b, and 2^c. These are joined at their corners by blind mortise-and-tenon joints 2^d and 2^e. Each of the side pieces 2^a and 2^b is provided with a tongue 2^f, and each side piece 3^a of the box is provided with a groove 3^f. The side pieces 3^a and 3^b and the end pieces 3^c and 3^d of the box are provided with blind mortises and tenon-joints at their meeting 90 corners. Each side piece of the bottom frame has intermediate its ends and on that side which lies toward the side board 3^a or 3^b of the box a pair of mortises 4^a 4^b, into which fit tenons on the end of the post 5 of the seat-support. Each of the posts 5 of the seat-support has intermediate its vertical ends a dovetailed mortise 5^a and a mouth-mortise 5^b, into which the end of a dovetailed block 6 may be engaged and dropped through the mouth 5^b 100 into the mortise 5^a. Each side board of the box has a similar dovetailed mortise 7, with

a mortise-mouth 7^a below it. The upper ends of the posts 5 are mortised into a frame 8 of four pieces, and these four pieces are also joined at their corners by blind mortise-joints.

- 5 At each corner of the bottom frame of the box and of the seat-frame are triangular blocks 9, with dovetailed tongues that engage in dovetailed mortises in the timbers and serve to unite the corners firmly together. On the 10 under side of the frame, intermediate the ends of each side piece, is a pair of mortises 2^g, which receive the blocks, and corresponding mortises 2^h are formed in each side piece of the box. A similar mortise 2^k is formed in 15 the top side of the side piece and in the top of the seat-frame and another one in the bottom of the seat-frame.

The entire box is assembled by setting up the seat-frame and the bottom frame, slipping the block 6 into place in the seat-frame, 20 forcing the side pieces 3^a and 3^b into place, with the tongue 2^f engaging in the groove and with the blocks 6 engaging in the mortises, and these pieces are then tied together by driving 25 the blocks 2^g into place from below. The end blocks 3^c and 3^d are forced into place and the corner fillet-blocks 9 of the entire structure properly inserted and the blocks 6^b inserted to bind the top of the seat-support and 30 the side of the box together.

The seat is built up substantially the same way with a bottom frame 10 10^a 10^b 10^c, the two end pieces and the back of this frame being provided with mortises or grooves 11, into 35 which are slipped dovetailed tenons, which terminate blocks 12. Preferably the blocks 12 extend entirely across the board from which the tenons project and serve as strengthening-ribs to prevent the warping and splitting 40 of the board.

After the back and two side pieces have been put in place they are secured by corner tie-fillets 13, and the seat-bottom is also secured and strengthened by corner-fillets 14. 45 The seat itself is secured to the seat-support by bolts or screws.

This entire structure may be prepared for assembly at the factory, shipped in the knock-down condition, and assembled when it 50 reaches its destination.

What I claim is—

1. In a vehicle-body, the combination of a

side piece of the frame provided with a mortise extending inward from its upper outer edge, a seat-post having a mortise-block 55 formed on its lower end, said block being adapted to slide laterally into said mortise, and a side piece of the box arranged to be secured to said side piece of the frame and to prevent said seat-post from being withdrawn 60 from the mortise substantially as described.

2. In a vehicle-body, the combination of a side piece of the frame having a laterally-extending lug, and provided with a mortise extending inward from its upper outer edge, a 65 seat-post having a mortise-block formed at its lower end, said block being adapted to slide laterally into said mortise, said seat-post having a mortise formed therein and a side piece of the box provided with a groove 70 adapted to engage said lug, and a mortise formed in said side piece of the box, a mortise-block adapted to enter said mortises in the seat-post and side pieces of the box to bind the same together, and means for securing 75 said side pieces together to prevent relative lateral movement, substantially as described.

3. In a vehicle-body, the combination of a side piece of the frame having a laterally-extending tongue 2^f, and a mortise extending 80 inward from its lower outer edge, a seat-post rising from said side piece, a side piece of the seat-frame secured at the top of said seat-post, and provided with a mortise extending 85 inward from its upper outer edge, a side piece of the box having a groove adapted to engage the tongue upon the side piece of the frame, a mortise adjacent to the mortise in the side piece of the frame, and a second mortise adjacent to the mortise in the side piece of the seat-frame, a mortise-block adapted to enter the mortises in the side pieces of the frame and box and a second mortise-block adapted 90 to enter the mortises in the side pieces of the seat-frame and vehicle-box, substantially as for the purpose described.

In testimony whereof I sign this specification in the presence of two witnesses.

LOUIS PRIEST.
